being had to the annexed perspective drawing, making a part of this Specification.

The design of my stove consists of the oak leaves A.A. - the stars B.B. at the corners, and the indented edge (C) on the top D. The side E. is ornamented with the Gothic moulding and arches F.F. the top moulding is ornamented with the scallops (H.H.) and the center ornament on the lower panel (a) consists of the oak leaves and acorns (b.b. & c.c.) The bottom plate G. has a leaf (d) at the corner, and the ornamental moulding (e.e.) around it; the edge moulding (f) has indentations or recesses (g,g) made in it. - H. is the leg.

Having thus described my design of Parlor Stove, what I claim as new and
